UNITED STATES PATENT OFFICE.

CHARLES MANLEY RAY, OF ASHEVILLE, NORTH CAROLINA.

RACK.

1,267,453.

Specification of Letters Patent. Patented May 28, 1918.

Application filed May 23, 1917. Serial No. 170,393.

To all whom it may concern:

Be it known that I, CHARLES MANLEY RAY, a citizen of the United States, and a resident of Asheville, in the county of Buncombe and State of North Carolina, have invented a new and useful Improvement in Racks, of which the following is a specification.

My invention is an improvement in racks, and has for its object to provide a device of the character specified, especially adapted for printers' use, wherein the rack consists of a fixed portion having means for securing the same to a table with the said fixed portion in inclined position, and a movable portion hinged to the fixed portion, said portions having means for holding the movable portion in alinement with the fixed portion or in horizontal position, and a tray connected with the movable portion and on the top thereof, when the said movable portion is in horizontal position.

In the drawings:—

Figure 1 is a perspective view of the improved rack,

Fig. 2 is a top plan view of the tray,

Fig. 3 is a perspective view with the rack folded to bring the tray into position for use,

Fig. 4 is a section on the line 4—4 of Fig. 3,

Fig. 5 is a section on the line 5—5 of Fig. 2, both views looking in the direction of the arrows adjacent the line.

The present embodiment of the invention is shown in connection with the table 1 of a printing press indicated at 2, and the improved rack comprises a fixed portion consisting of a bottom 3, a lower side wall 4 and end walls 5. Angle brackets 6 are secured to the bottom of the fixed portion by screw bolts 7 and to the table 1 in any suitable or desired manner. These angle brackets support the fixed portion of the rack in the inclined position shown and a movable or swinging portion is hinged to the ends 5 of the fixed portion. This movable portion consists of a rear or bottom wall 8 and ends 9 secured to the bottom or rear wall, and these ends 9 are connected to the ends 5 of the fixed portion by hinges 10. As shown, each hinge consists of two leaves, one of which is secured to an end 9 and the other to an end 5, and the ends 5 are beveled at their top in opposite directions as indicated at 11 and 12 respectively for engagement by

the beveled ends 13 of the ends 9, to hold the bottom or rear wall 8 of the movable portion in the position of Fig. 1, or in the position of Figs. 3 and 4, that is, in inclined position, and in the plane of the bottom 3, or in horizontal position at an angle to the bottom 3, and overhanging the said fixed portion.

A tray is supported by the bottom 8 of the movable portion, the said tray consisting of a fixed portion secured to the bottom 8, and a removable portion detachably connected with the said bottom and with the fixed portion. The fixed portion consists of a front wall 14 having at its ends extensions 15, and the lower edges of the said front wall 14 and extensions 15 are flanged as indicated at 16 in dotted lines in Fig. 2, and said flanges are secured to the bottom 8 of the movable portion. The removable portion of the tray consists of a bottom 17, a rear wall 18 and end walls 19, and the bottom is of a width to extend from the rear of the tray to the wall 14 of the fixed portion. A portion of the flange 16 of the wall 14 at the center of the said wall is separated and offset upwardly to form a tongue 20 which engages over the edge of the bottom 17 when the removable portion is in place, as shown more particularly in Fig. 4. The rear wall of the removable portion of the tray is a bar of wood or the like as shown at 21, and the end walls 19 are connected with the ends of the bar and have extensions 22 engaging the rear or outer face of the bar. A tongue 23 is struck up from the rear edge of the bottom 17 and this tongue is secured to the inner face of the bar, the said tongue being at the center of the bar. The inner upper corner of the bar is beveled as indicated at 24 and a latch is provided at the rear of the bottom 8 for connecting the removable portion of the tray to the said bottom to hold it in place. This latch mechanism consists of a catch 25 on the bottom 8, and a latch lever 26 pivoted to a plate 27 secured to the bar, the latch being normally pressed into engagement with the catch by a coil spring 28. The latch lever has a finger-piece as shown for convenience in releasing the same, and when the said lever is engaged with the catch the removable portion of the tray is held firmly in place on the bottom 8 of the movable portion of the rack.

It will be noticed from an inspection of

Figs. 1 and 3, that the end walls 15 of the fixed portion of the tray are beveled, and that these walls fit snugly outside the walls 19. In use, the device may be arranged as shown in Figs. 3 and 4, or as shown in Fig. 5, or the removable portion of the tray may be removed.

When in the position of Fig. 1, the top of the rack is open and boxes of considerable length may be supported by the rack as shown in Fig. 1. When the parts are in the position of Figs. 3 and 4, papers may be placed in the fixed portion of the rack and in the tray and if the said papers are of too great size for the tray the removable portion may be removed.

I claim:-

1. A device of the character specified comprising a fixed portion having means for connecting the same to a table to hold the said fixed portion in an inclined position with respect to the table, said fixed portion comprising a bottom wall, end walls and a lower side wall, the end walls being extended above the bottom wall and beveled at both corners, a movable portion consisting of a bottom and end walls secured to the underface of the bottom and hinged to the end walls of the fixed portion and beveled at their hinged ends to engage either beveled face of the end wall to support the movable portion in alinement with the fixed portion or in horizontal position.

2. A device of the character specified comprising a fixed portion having means for connecting the same to a table to hold the said fixed portion in inclined position with respect to the table, said fixed portion comprising a bottom wall, end walls and a lower side wall, the end walls being extended above the bottom wall and beveled at both corners, a movable portion consisting of a bottom and end walls secured to the underface of the bottom and hinged to the end walls of the fixed portion and beveled at their hinged ends to engage either beveled face of the end wall to support the movable portion in alinement with the fixed portion 55

3. A device of the character specified comprising a fixed portion having means for connecting the same to a table to hold the said fixed portion in an inclined position 60 with respect to the table, said fixed portion comprising a bottom wall, end walls and a lower side wall, the end walls being extended above the bottom wall and beveled at both corners, a movable portion consisting of a bottom and end walls secured to the underface of the bottom and hinged to the end walls of the fixed portion and beveled at their hinged ends to engage either beveled face of the end wall to support the movable portion in alinement with the fixed portion 65 or in horizontal position, said movable portion supporting a tray.

CHARLES MANLEY RAY.
